UNITED STATES PATENT OFFICE

2,095,214

BUILDER MECHANISM

John S. Furtado, Jr., New Bedford, Mass.

Application March 9, 1934, Serial No. 714,813

21 Claims. (Cl. 242—43.6)

This invention pertains to builder mechanism for spinning frames, twisting frames, or similar textile machines, and relates more particularly to an improved bunch builder and traverse mechanism, and to a method of winding yarn upon bobbins or the like by the use of such mechanism.

Bobbins employed in automatic weft replenishing looms are desirably provided with a small bunch of yarn, for example, near the end 10 of the bobbin, for engagement by the feeder of the replenishing mechanism of the loom in order to insure efficient operation of such mechanism. One object of the present invention is to provide 15 improved and effective means, applicable without substantial difficulty to old or new frames of usual commercial types, for building a traverse-wound preliminary bunch on the bobbin, and designed automatically to change over from bunch building to a longer traverse after a predetermined 20 period of operation.

The builder motion of the usual ring frame forms a yarn mass having a long taper at its lower end. Such a yarn mass contains from 5% to 10% less yarn than would be the case if the 25 yarn mass had a shorter taper or abrupt shoulder at its lower end. A further object of the invention is to provide builder mechanism, applicable to ring frames of ordinary type, such that more than the usual amount of yarn may be wound on a given bobbin as, for example, by shortening and making more abrupt the taper of the 30 yarn mass at the lower end of the bobbin. By placing more yarn on the individual bobbin the frequency of doffing is decreased and thus the 35 efficiency of the winding or twisting operation is increased and a lesser number of piecings-up of the yarn are necessary in subsequent operations.

In most prior bunch building mechanisms the 40 transfer from bunch building to regular traverse has been abrupt, sometimes jerking the yarn so sharply as to cause breakage. A further object of my invention is to provide builder mechanism capable of winding the preliminary bunch, followed by a traverse of intermediate length there- 45 by to place an abnormally large amount of yarn at the lower part of the bobbin, and then in turn to follow this intermediate traverse by the regular traverse, the change from one traverse to the next being accomplished smoothly and without 50 damage to the yarn.

Other objects and advantages of the present invention will hereinafter be set forth and more fully described with reference to the selected embodiment of the invention disclosed by way of 55 example in the accompanying drawings, in which:

Fig. 1 is a fragmentary and more or less diagrammatic view of the lower right-hand part of a ring spinning frame having my improved bunch builder mechanism incorporated therein;

Fig. 2 is a fragmentary side elevation to larger 5 scale, viewed from the left-hand side of Fig. 1, showing the bunch builder mechanism removed from the frame and with the parts in the position which they occupy during the long traverse winding operation;

Fig. 3 is a fragmentary end elevation, partly in section, of the builder mechanism illustrated in Fig. 2;

Fig. 4 is a view from the right-hand side of Fig. 1, but to larger scale, but omitting certain 15 parts;

Fig. 5 is a fragmentary view illustrating some of the parts of the builder mechanism shown in Fig. 2, but in the position which they occupy 20 near the end of the short traverse winding operation;

Fig. 6 is a view similar to Fig. 5, with parts omitted, indicating the position of the parts near the beginning of the short traverse wind;

Fig. 7 is a similar view illustrating parts which 25 are concerned in the bunch building operation as they are disposed at an intermediate point in the bunch building operation;

Fig. 8 is a view generally similar to Fig. 7 but with additional elements included;

Fig. 9 is a front elevation of the parts shown in Fig. 8;

Fig. 10 is a view similar to Fig. 8, but showing the parts in the position which they occupy at the completion of the bunch building operation;

Fig. 11 is an elevation showing some of the parts of Fig. 8 but viewed from the opposite side;

Fig. 12 is an elevation illustrating a pawl device 40 for driving a part of the short traverse mechanism;

Fig. 13 is an elevation of a second pawl device for resetting the short traverse mechanism;

Fig. 14 is a fragmentary horizontal section 45 illustrating an improved traverse advancing means;

Fig. 15 is a front elevation of some of the parts shown in Fig. 14;

Fig. 16 is a fragmentary elevation similar to Fig. 15, but indicating another position of the 50 parts;

Figs. 17, 18 and 19 are fragmentary views illustrating details of the traverse advancing mechanism whereby a progressively increasing 55 advance is obtained;

Fig. 20 is a side elevation of a bobbin wound in accordance with usual practice;

Fig. 21 is a side elevation of a bobbin made in accordance with my present method and showing the increased amount of yarn thereon;

Fig. 22 is a side elevation of a bobbin with a preliminary bunch wound thereon;

Figs. 23, 24, 25 and 26 are fragmentary diagrammatic views, to large scale, illustrating successive steps in forming the bunch in accordance with my present method;

Fig. 27 is a fragmentary diagrammatic section illustrating the formation of the short traverse wind in succession to the bunch; and

Fig. 28 is a view similar to Fig. 27, illustrating the completion of the bunch and the short traverse wind and the beginning of the long or normal traverse wind.

My improved builder mechanism is here illustrated as applied to a ring spinning frame of conventional type. As shown in Fig. 1, this frame comprises the right-hand end member 1 forming a support for one end of the fixed spindle rail 2 carrying a series of spindles 3 on which bobbins 4 may be mounted. A vertically movable ring rail 5 is supported by a plurality of lifter rods 6 (but one of these rods being shown), these rods being guided in bearings on the rail 2 and having their lower ends resting on rollers carried by levers 7. Only one of these levers is illustrated in the present drawings, but each lever may be understood to be pivoted as at 8 upon a bracket carried by the rail 2 and as being provided with a counterweight 9, the counterweights being normally operative to lift the ring rail and the parts connected thereto. The lever 7 which is illustrated in Fig. 1 is provided near its free end with a foot-rest or treadle 10 by means of which it may be swung in a clockwise direction so as to lower the ring rail to doffing position, and is also furnished with an upstanding arm 11 carrying a sector over which a chain 12 passes and to which one end of the chain is secured. Preferably a link 11a connects arms 11 of the several levers so that they rock unisonally. The chain 12 passes over a guide pulley 13 and then downwardly to a winding drum forming a part of the builder mechanism 14. The parts thus far described are of usual and well known construction.

The builder mechanism comprises the traverse or builder lever 15 (Fig. 2) pivotally mounted upon a stud at 16 supported by one end member of the machine frame. Preferably this traverse lever is furnished with a counterweight 17, as usual. The traverse lever has a lateral arm 18 (Fig. 3) supporting a cam follower roll 19 adapted at times to engage the usual main or long traverse cam 20. This cam is mounted on a shaft 21 supported in suitable bearings in the machine frame and is driven at a proper rate of speed by gearing (not shown) from the drive shaft of the frame. The main traverse cam 20 is furnished with active portions or lobes 22 (Fig. 4) and intervening depressions, (three such lobes being illustrated) the lobes and depressions acting alternately to depress the traverse lever and to allow it to rise in response to the action of the counterweight 17, the latter tending to keep the roll 19 in contact with the peripheral edge of the cam 20.

Near its free extremity the traverse lever 15 supports a transverse stud shaft 23 (Fig. 2) on which turns a chain drum 24 (Fig. 15) having fast thereto a worm wheel 25 protected by a

housing 26. One end of the chain 12 is secured to the chain drum 24 and thus, as the traverse lever oscillates up and down, the lever comprising the arms 7 and 11 is rocked and the ring rail is correspondingly raised and lowered.

The worm wheel 25 meshes with a worm 27 (Figs. 2 and 14) fixed on a shaft 28 which turns in suitable bearings 15a carried by the lever 15. This shaft 28 projects beyond the free end of the traverse lever 15 and its projecting end has fixed thereto a ratchet wheel 29 which is intermittently turned by a pawl 30 (Fig. 15). This pawl is pivoted at 31 to an arm of a pawl carrier 31a free to turn on the shaft 28 and having a counterweight 32 normally tending to restore the pawl carrier 31a substantially to the position of Fig. 15 after being depressed. The counterweight 32 has an arcuate slot 33 which receives a pin 33a carried by an arm 34 of a control member 35 free to turn on the shaft 28 adjacent to the pawl carrier and having a pair of spaced stops 36 and 37 adapted by contact with contiguous parts of the traverse lever 15 to limit rotation of the controller 35 in either direction. The ultimate limit of movement of the pawl carrier in either direction is thus determined. The pawl has an actuating arm 38 adapted to be engaged by the lower end of a rod 39 (Fig. 1) conveniently secured at its upper end to the fixed spindle rail 2. Each time the traverse lever 15 rises, the arm 38 is depressed by engagement with the end of rod 39 and thus advances the ratchet wheel 29 and turns the shaft 28.

For reasons more fully described hereafter, it is desirable during the early stages of the building operation, to advance the traverse to a slight degree, that is, to an amount less than the normal advance, and, in particular, progressively to increase the advance of the traverse from a minimum amount up to the normal or usual amount. To this end I prefer to make the teeth of ratchet wheel 29 quite small, so that the maximum or normal throw of pawl 30 is sufficient to turn the ratchet wheel through an arc equivalent to several of the ratchet teeth. I then provide for limiting the effective throw of this pawl at the beginning of the operation so that it moves the ratchet wheel only one tooth space, for example, but at each successive oscillation of the traverse lever the throw of the pawl is increased until it is restored to normal action.

To accomplish this result I provide a rack bar 42 (Figs. 14 to 19 inclusive) arranged to slide parallel to the shaft 28 in bearings 15b carried by lever 15. This rack bar 42 has teeth which mesh with a worm 42a fixed to the shaft 28. At its outer end the bar 42 has an inclined cam or beveled surface 43 (Figs. 17, 18 and 19) adapted to cooperate with an inclined cam surface 44 on the pawl carrier 31a. At the beginning of the operation, the cam surfaces 43 and 44 occupy the relative positions shown in Fig. 17, and when thus positioned the pawl carrier is permitted to rise after each actuation only enough to allow the pawl to advance one tooth, for example, along the ratchet wheel. The shaft 28 is thus turned a very small amount on the next forward movement of the pawl, and the chain 12 is wound up very slightly so that the advance of the traverse along the bobbin axis is slight. However, each stroke of the pawl 30 not only turns the ratchet wheel and shaft 28 and thus winds up the chain, but it also retracts the rack bar 42 so that the cam surface 43 gradually recedes from the cam surface 44, thus allowing the pawl carrier to rise higher at each

oscillation. Thus the advance of the traverse grows longer and longer with each oscillation of the traverse lever 15 until the cam surface 44 is entirely clear of the cam surface 43, as shown 5 in Fig. 19, for example. Thereafter each oscillation of the traverse lever 15 results in a full stroke of pawl 30 and a consequent normal take-up of chain 12 and normal advance of the traverse.

For building the preliminary bunch on the 10 bobbin at the start of the operation, I prefer to provide the main traverse cam 20 with a hub 45 to which is secured a bunch building cam 46 (adapted to impart a short oscillatory movement to lever 15) and a pinion 47 (Figs. 3 and 7 to 11, 15 inclusive). This cam 46 is here illustrated as provided with six lobes 48^a (Fig. 7) with intervening depressions, but a greater or lesser number of lobes may be provided, as desired. This cam 46 at times cooperates with a flange or annular rib 20 48 (Fig. 9) projecting from one face of a mutilated or intermittent gear 49 mounted to turn freely on a stud shaft 50 carried by an upstanding part 18^a of bracket 18 (Fig. 3). This flange or rib 48 is 25 concentric with the axis of shaft 50 throughout the major part of its circumference, but through an arc of approximately 120° or thereabouts this flange is omitted, leaving a deep gap or recess 51 (Figs. 7, 8 and 10).

The gear 49, which carries flange 48, is furnished 30 with teeth which normally mesh with the teeth of pinion 47, but the toothed rim of the gear also has a gap which registers with the gap 51. A counterweight 53 (Figs. 9 and 11) is adjustably secured to the gear 49 as, for example, by means 35 of a slotted segment 53^a and a bolt 53^b so that this counterweight may be adjusted circumferentially about the axis of the shaft 50, thereby to vary its angular relation to the gap 51. The position of the counterweight determines the number of teeth 40 of gear 49 with which the pinion 47 will engage as the pinion turns clockwise (Fig. 7) before the pinion reaches the gap in the gear.

When the machine is to be doffed, the traverse 45 lever 15 is lowered by the operator, thus freeing the gear 49 from pinion 47, whereupon the counterweight on gear 49 automatically restores the latter to its normal or starting position. By adjusting the counterweight, the gap in the gear 50 may be disposed at a greater or lesser distance from the initial point of engagement of the pinion with the gear, and thus the angle through which the gear 49 will turn before the cam 48 enters the gap 51 is initially determined by adjustment of the counterweight.

55 Preferably and in order to ease the relative movement of the parts when the pinion 47 and cam 46 enter the gap 51, the end portion of the flange 48 is formed as a separate part 48^a pivotally secured to the main body of the gear 49 and normally held outwardly by a spring-pressed pin 48^b (Figs. 8 and 10) housed in a socket member carried by the gear 49. This pivoted portion or latch 48^a preferably projects outwardly and eccentrically to the main part of the flange 48, 60 forming a rounded head portion 48^c which is engaged by the cam 46 as the latter nears the gap 51 and yields inwardly and thus cushions the cam 46 as the latter runs off the stationary part of flange 48 and enters the gap 51. By continuing to engage the cam 46, after the latter has 65 entered the gap 51, (Fig. 10), this head member 48^c prevents premature resetting of the gear 49 by the counterweight 53.

70 Preferably, after the bunch has been completed and before the normal traverse is com-

menced, I wind a predetermined number of relatively short layers (intermediate in length between those used in building the bunch and those which form the body of the yarn mass) thereby to shorten the taper of the yarn mass at the lower 5 end of the bobbin and thus to increase the amount of yarn which is wound. To this end I provide the shaft 21, which carries the main or long traverse cam 20, with a short traverse cam 55 (Fig. 3). This cam turns at the same rate as the main 10 traverse cam 20 and is here shown as having the same number of lobes with intervening spaces. The peripheral edge of the cam 55 at times engages a cam follower roll 56 (Figs. 2, 5 and 6) carried by a lever 57 pivoted for adjustment on a 15 stud 58 carried by an upstanding arm 59 of a bracket 60 (Fig. 3) secured to traverse lever 15.

This lever 57 has a head portion 61 provided with a smoothly curved contact surface 62 (which may be replaced by a roller, if desired) adapted 20 to engage the peripheral edge of a cam-follower disk 63 mounted to turn freely on a stud 64 projecting from the bracket 60. The peripheral edge of the cam-follower disk 63 is substantially concentric with its axis, except throughout an arc of 25 approximately sixty degrees where it is depressed to form a gap 63^a (Figs. 5 and 6) into which the head 61 of the lever 57 may at times drop. The surfaces defining the ends of the gap 63^a merge 30 smoothly into the concentric portion of the periphery of the cam to provide easy descent and ascent of the head 61. When the cam 46 runs off into the gap 51 the cam 55 engages the follower roll 56, whereupon the short traverse winding begins and continues until the head 61 of lever 35 57 falls into the gap 63^a in the disk 63.

A ratchet wheel 65 (Figs. 2, 3, 5 and 6) is secured 40 to the hub of disk 63 in coaxial relation to the latter. A driving pawl 66 (Figs. 2, 5 and 12) normally engages the teeth of wheel 65 and intermittently turns the latter in a counterclockwise direction, as viewed in Figs. 2 and 5. This pawl is carried by a lever 66^a mounted to rock freely on the stud 64. This lever is provided with a counterweight 67 tending to swing the lever in a clockwise 45 direction, as viewed in Figs. 2 and 5, so as to retract the pawl 66, and the latter is so weighted as to tend to engage the ratchet wheel, but is furnished with a tail 68 by means of which it may be lifted out of action. The pawl carrying 50 lever 66^a has an upwardly elongate extension 69 which lies in the path of an adjustable stud 70 (Figs. 2 and 5) projecting from the face of cam 55. Thus at each rotation of cam 55 the stud 70 55 engages the part 69 thereby rocking the pawl carrying lever 66^a so as to advance the ratchet wheel 65 if pawl 66 is then in engagement with the latter. The stud 56^a which supports cam follower roll 56 projects laterally (Fig. 3) into the plane of the tail 68 of pawl 66, and when the head 60 61 of lever 57 drops into the gap 63^a of disk 63, the stud 56^a engages the tail of pawl 66, (Fig. 2) thus lifting the pawl out of engagement with the ratchet wheel so as to stop further rotation of the latter. 65

70 While the head 61 of lever 57 rides on the concentric portion of the periphery of disk 63, the head 61 with its roll 56 transmits oscillatory motion from cam 55 to the traverse lever 15, at the same time holding the traverse lever down so low that the main traverse cam 20 can not effectively engage the roll 19. However, when head 61 drops into gap 63^a, the traverse lever rises, by the action of weight 17, until the roll 19 comes into the 75

field of action of the cam 20, whereupon normal traverse begins.

In order to restore the head 61 of lever 57 to the outer, concentric periphery of cam 55 at the start of a new operation, I provide a second pawl 71 (Figs. 2, 5 and 13) mounted on a second pawl carrying lever 71^a turning freely on the stud 64 and having a counterweight 72 tending to turn the lever in a clockwise direction (Figs. 2 and 5) so as to retract the pawl 71. The pawl 71 is so weighted (as by a tailpiece 73) that it tends to engage the ratchet wheel 65. A fixed pin 71^b limits upward movement of the pawl carrying arm 71^a. A rod 74 is pivotally connected at its lower end to the counterweight 72 and has an elongate hook portion 75 at its upper end having free sliding engagement with the shaft 21. When the traverse lever 15 is lowered for doffing, the bend of hook 75 engages the shaft 21, and continued downward movement of the traverse lever thus actuates pawl 71 to turn the ratchet 65 and its associated disk 63 far enough to raise the head 61 of lever 57 up and out of gap 63^a onto the concentric portion of the cam ready to start another revolution.

Although the operation of the device has already been explained, it may briefly be restated as follows:—Assuming that the frame has been in operation and that the bobbins have been filled, the frame is first stopped and the parts are placed in position for doffing. To do this, the operator places his foot on the treadle 10, thus swinging the lever 7 downwardly and lowering the ring rail, at the same time slackening the chain 12 and allowing the traverse lever 15 to descend part way. Retaining means (not shown) are sometimes provided to hold the treadle in depressed condition until again released. The operator then inserts a crank in a socket in the end of shaft 28 as is usual, and while holding the pawl 30 out of action, rotates shaft 28 so as to unwind the chain 12 from the drum 24, thus allowing traverse lever 15 to descend to its lowest position. In thus reversing the shaft 28, the rack bar 42 is moved outwardly until its beveled or cam end 43 again engages the cam 44 on the ratchet wheel 29 (as shown in Fig. 17). The descent of bar 15 as already described causes the hook 75 to engage shaft 21, thereby actuating the pawl 71 so as to turn the disk 63 to the starting position (Fig. 6) wherein the head 61 of lever 57 occupies a position just to the right of the gap 63^a. Furthermore, the lowering of traverse lever 15 to the doffing position wholly separates the cam 46 from the gear 49, thus allowing the counterweight 53 to restore the gear 49 to starting position. As already stated, the position of adjustment of the counterweight 53 automatically determines the number of teeth of the gear 49 which intervene between the gap 51 and the pinion 47 at starting.

When the operator releases the treadle 10 from its retaining means, the lever 15 rises slightly until flange 48 engages cam 46, the teeth of pinion 47 and gear 49 at the same time coming into mesh.

When the machine is started, the traverse lever 15 is actuated by the cam 46, the latter imparting a short vibration to the traverse lever, thus providing a very short up-and-down movement to the ring rail. During this movement a series of layers B of yarn, as indicated in Figs. 23 to 26 inclusive, for example, are disposed at the lower end of the bobbin so as to form the preliminary bunch B' (Fig. 22). The number of layers thus wound to form the bunch depends upon the number of lobes of the cam 46 and also on the initial

adjustment of the counterweight 53. As here shown, the bunch comprises four layers, but it is to be understood, as already suggested, that a greater or lesser number may be provided, if desired. The cam 46 continues to operate so long as the pinion 47 engages teeth of the gear 49, but it may be noted that at each downward stroke of lever 15 the pawl 30 advances the ratchet wheel 29 so as to turn the shaft 28 and to take up the chain 12. At the beginning of the operation 10 pawl 30 has but a very short effective stroke so that the shaft 28 turns but little and the chain is taken up so slightly that there is but little advance of the traverse during the bunch building, although a slight advance has been indicated in Figs. 23 to 26 inclusive.

When cam 46 runs off into the gap 51 the cam 55 operatively engages the follower roll 56. Thereafter the short traverse winding P begins and continues (Fig. 27) until the head 61 of lever 57 drops into the gap 63^a in disk 63. During this short traverse, the cam surfaces 43 and 44 continue to recede, slowly but gradually increasing the advance of the traverse, but by reason of this short traverse wind in succession to the bunch 25 building operation, the lower part P of the yarn mass is built up with a much more abrupt shoulder than is usual, with a resultant increase in the amount of yarn on the bobbin of from 5% to 10%.

When the head 61 of lever 57 drops into the gap 63^a, the cam 20 engages the roll 19, whereafter the normal traverse is continued throughout the winding operation. At about the time that the cam 20 engages roll 19, the cam surfaces 35 43 and 44 disengage so that thereafter the advance of the traverses is uniform while the main yarn mass M is being built. The long traverse winds succeeding the formation of the short traverse are indicated in Fig. 28. The operation 40 thus continues until the bobbin is full, whereupon the machine is again doffed as above described and the operation repeated.

While I have herein illustrated certain desirable mechanism for accomplishing the desired result, I wish it to be understood that the invention is not necessarily limited to the precise arrangement of parts herein disclosed, but that any other and equivalent mechanism operative to perform the desired function and falling within 50 the scope of the appended claims is to be regarded as a part of my invention.

I claim:

1. A builder mechanism for use in a machine of the class described, said builder mechanism comprising a traverse lever, cam means operative to impart a bunch building motion to said lever, cam means operative at the completion of bunch building to impart a short traverse movement to said lever thereby to form the lower part of the 60 yarn mass, and cam means operative to impart a long traverse movement to said lever thereby to form the main part of the yarn mass.

2. A builder mechanism for use in a machine of the class described, said builder mechanism comprising a traverse lever, cam means operative to impart a bunch building motion to said lever, cam means operative to impart a short traverse movement to said lever, cam means operative to impart a long traverse movement to said lever, 70 and means operative automatically to cause said several cam means to come into effective operation in succession.

3. A builder mechanism for use in a machine of the class described, said builder mechanism 75

comprising a traverse lever, bunch forming means operative to oscillate the lever through an arc of short amplitude, short traverse means operative to oscillate the lever through an arc of greater amplitude, and long traverse means operative to oscillate the lever through an arc of still greater amplitude, and mechanism operative automatically to cause the several lever oscillating means to come into effective operation successively.

4. A builder mechanism for use in a machine of the class described, said builder mechanism comprising a traverse lever, cam means operative to impart a bunch building motion to said lever, cam means operative at the completion of bunch building to impart a short traverse movement to said lever thereby to form the lower part of the yarn mass, cam means operative at the conclusion of the short traverse movement to impart a long traverse movement to said lever thereby to form the main part of the yarn mass, and traverse advancing means operative to impart a progressively increasing advance during a portion at least of the building operation.

5. A builder mechanism for use in a machine of the class described, said builder mechanism comprising a traverse lever, a main traverse cam operative at times to oscillate the traverse lever through an arc of normal extent whereby to produce a normal traverse, means operative at the beginning of the building action to prevent effective operation of the main traverse cam, a short traverse cam operative at times while the main traverse cam is ineffective to oscillate said lever through an arc of intermediate extent whereby to produce a short traverse, means operative at the initiation of the building action to prevent effective operation of the short traverse cam, and a bunch building cam operative while the main traverse cam and the short traverse cam are ineffective to oscillate the lever through an arc of short extent, thereby to form a traverse wound preliminary bunch adjacent to one end of the bobbin.

6. A bunch builder mechanism for use in a machine of the class described, said builder mechanism comprising a traverse lever, a main traverse cam operative at times to oscillate said lever through an arc sufficient to produce a normal or long traverse, a pinion coaxial with said main cam and turning therewith, a bunch builder cam secured to the pinion, a freely rotatable mutilated gear supported by the traverse lever, said gear being cooperable with said pinion, an annular flange coaxial with said gear and fixed relatively to the latter, said flange being of such diameter that when engaged by the bunch builder cam the lever is held out of the field of action of the main traverse cam, the flange and mutilated gear having registering segmental gaps adapted at times to receive the bunch builder cam and the pinion respectively thereby freeing the traverse lever for movement toward the field of action of the main traverse cam, and an adjustable counterweight operative when the pinion is freed from the mutilated gear to reset the latter to a predetermined position.

7. A bunch builder mechanism for use in a machine of the class described, said builder mechanism comprising a traverse lever, a main traverse cam operative at times to oscillate said lever through an arc sufficient to produce a normal or long traverse, a pinion coaxial with said main cam and turning therewith, a bunch builder cam secured to the pinion, a freely rotatable

mutilated gear supported by the traverse lever, said gear being cooperable with said pinion, an annular flange coaxial with said gear and fixed relatively to the latter, said flange being of such diameter that when engaged by the bunch builder cam the lever is held out of the field of action of the main traverse cam, the flange and mutilated gear having registering segmental gaps adapted at times to receive the bunch builder cam and the pinion respectively thereby freeing the traverse lever for movement toward the field of action of the main traverse cam, the flange and mutilated gear having a resiliently yieldable portion adjacent to one edge of the gap in said flange.

8. A bunch builder mechanism for use in a machine of the class described, said builder mechanism comprising a traverse lever, a main traverse cam operative at times to oscillate said lever through an arc sufficient to produce a normal or long traverse, a pinion coaxial with said main cam and turning therewith, a bunch builder cam secured to the pinion, a freely rotatable mutilated gear supported by the traverse lever, said gear being cooperable with said pinion, an annular flange coaxial with said gear and fixed relatively to the latter, said flange being of such diameter that when engaged by the bunch builder cam the lever is held out of the field of action of the main traverse cam, the flange and mutilated gear having registering segmental gaps adapted at times to receive the bunch builder cam and the pinion respectively thereby freeing the traverse lever for movement toward the field of action of the main traverse cam, and a spring-pressed member operative, after the bunch builder cam enters the gap, to prevent reverse movement of the mutilated gear until the traverse lever has been moved downwardly preparatory to doffing.

9. A bunch builder mechanism for use in a machine of the class described, said builder mechanism comprising a traverse lever, a main traverse cam operative at times to oscillate said lever through an arc sufficient to produce a normal or long traverse, a pinion coaxial with said main cam and turning therewith, a bunch builder cam secured to the pinion, a freely rotatable mutilated gear supported by the traverse lever, said gear being cooperable with said pinion, an annular flange coaxial with said gear and fixed relatively to the latter, said flange being of such diameter that when engaged by the bunch builder cam the lever is held out of the field of action of the main traverse cam, the flange and mutilated gear having registering segmental gaps adapted at times to receive the bunch builder cam and the pinion respectively thereby freeing the traverse lever for movement toward the field of action of the main traverse cam, means normally tending to reverse the mutilated gear and restore it to a predetermined normal or starting position, and means operative after the bunch building cam enters the gap in said flange to prevent reverse movement of the mutilated gear until the apparatus is made ready for doffing.

10. A builder mechanism for use in a machine of the class described, said builder mechanism comprising a traverse lever, a main traverse cam operative at times to oscillate the traverse lever through an arc of normal extent whereby to produce a normal traverse, a short traverse cam operative at the beginning of the building action to prevent effective operation of the main traverse cam, said short traverse cam being operative at

- times, while the main traverse cam is ineffective, to oscillate said lever through an arc of intermediate extent, thereby to produce a short traverse, a bunch building cam operative at the initiation 5 of the building action to prevent effective operation of the short traverse cam, said bunch building cam being operative while the main traverse cam and the short traverse cam are ineffective to oscillate the lever through an arc of short extent, thereby to form a preliminary bunch adjacent to one end of the bobbin, and means operative automatically to determine the period of 10 operation of the bunch building cam before the short traverse cam becomes effective.
- 15 11. A builder mechanism for use in a machine of the class described, said builder mechanism comprising a traverse lever, a main traverse cam operative at times to oscillate the traverse lever through an arc of normal extent whereby to produce a normal traverse, a short traverse cam operative at the beginning of the building action to prevent effective operation of the main traverse cam, said short traverse cam being operative at times, while the main traverse cam is ineffective, 20 to oscillate said lever through an arc of intermediate extent, thereby to produce a short traverse, a bunch building cam operative at the initiation of the building action to prevent effective operation of the short traverse cam, said bunch building cam being operative while the main traverse cam and the short traverse cam are ineffective to oscillate the lever through an arc of short extent, thereby to form a preliminary bunch adjacent to one end of the bobbin, and means 25 adjustable at will selectively to predetermine the length of the period of operation of the bunch building cam before the short traverse cam becomes effective.
12. A builder mechanism for use in a machine 40 of the class described, said builder mechanism comprising a traverse lever, a main traverse cam operative at times to oscillate the traverse lever through an arc of normal extent whereby to produce a normal traverse, a short traverse cam operative at the beginning of the building action to prevent effective operation of the main traverse cam, said short traverse cam being operative at times, while the main traverse cam is ineffective, to oscillate said lever through an arc of intermediate extent, thereby to produce a short traverse, a bunch building cam operative at the initiation of the building action to prevent effective operation of the short traverse cam, said bunch building cam being operative while the 45 main traverse cam and the short traverse cam are ineffective to oscillate the lever through an arc of short extent, thereby to form a preliminary bunch adjacent to one end of the bobbin.
13. A builder mechanism for use in a machine 60 of the class described, said builder mechanism comprising a traverse lever, a main traverse cam operative at times to oscillate said lever throughout an arc sufficient to produce a normal or long traverse, a short traverse cam coaxial with said main cam and turning with the latter, a freely rotatable ratchet wheel supported by the traverse lever, a cam-follower disk fast to the ratchet wheel, a pawl for intermittently advancing the ratchet wheel, a drive element carried by the 65 short traverse cam, and a pawl carrier engageable by said drive element as the cam rotates, thereby to advance the pawl and ratchet wheel.
14. A builder mechanism for use in a machine 70 of the class described, said builder mechanism comprising a traverse lever, a main traverse cam

operative at times to oscillate said lever throughout an arc sufficient to produce a normal or long traverse, a short traverse cam coaxial with said main cam and turning with the latter, a freely rotatable ratchet wheel supported by the traverse lever, a pawl for intermittently advancing the ratchet wheel, a cam-follower disk coaxial with and fixed to the ratchet wheel, said disk cooperating at times with the short traverse cam, thereby to cause a short traverse motion of the traverse lever, and means operative to impart a bunch building motion to the traverse lever at the beginning of the building operation.

15. A builder mechanism for use in a machine of the class described, said builder mechanism comprising a traverse lever, a main traverse cam operative at times to oscillate said lever throughout an arc sufficient to produce a normal or long traverse, a short traverse cam coaxial with said main cam and turning with the latter, a freely rotatable ratchet wheel supported by the traverse lever, a pawl for intermittently advancing the ratchet wheel, a cam follower coaxial with and fixed to the ratchet wheel, a motion transmitting element interposed between the short traverse cam and the cam follower, the cam follower being of such dimensions that when the transmission element is interposed between the cam follower and the short traverse cam the traverse lever is held out of the field of action of the long traverse cam, the cam follower having a recess adapted at times to receive said motion transmitting element, thereby freeing the traverse lever for movement into the field of action of the long traverse cam.

16. A builder mechanism for use in a machine of the class described, said builder mechanism comprising a traverse lever, a main traverse cam operative at times to oscillate said lever throughout an arc sufficient to produce a normal or long traverse, a short traverse cam coaxial with said main cam and turning with the latter, a freely rotatable ratchet wheel supported by the traverse lever, a pawl for intermittently advancing the ratchet wheel, a cam follower coaxial with and fixed to the ratchet wheel, a motion transmitting element interposed between the short traverse cam and the cam follower, the cam follower being of such dimensions that when the transmission element is interposed between the cam follower and the short traverse cam the traverse lever is held out of the field of action of the long traverse cam, the cam follower having a recess adapted at times to receive said motion transmitting element, thereby freeing the traverse lever for movement into the field of action of the long traverse cam, and means operative to throw said pawl out of action when the motion transmitting element enters the recess in the cam follower.

17. A builder mechanism for use in a machine of the class described, said builder mechanism comprising a traverse lever, a main traverse cam operative at times to oscillate said lever throughout an arc sufficient to produce a normal or long traverse, a short traverse cam coaxial with said main cam and turning with the latter, a freely rotatable ratchet wheel supported by the traverse lever, a pawl for intermittently advancing the ratchet wheel, a cam follower coaxial with and fixed to the ratchet wheel, a motion transmitting element interposed between the short traverse cam and the cam follower, the cam follower being of such dimensions that when the transmission element is interposed between the

cam follower and the short traverse cam the traverse lever is held out of the field of action of the long traverse cam, the cam follower having a recess adapted at times to receive said motion transmitting element, thereby freeing the traverse lever for movement into the field of action of the long traverse cam, a resetting pawl cooperable with said ratchet, and means automatically actuated, during the operation of placing the parts in doffing position, to operate said pawl, thereby to advance the ratchet until the motion transmitting element is moved from out the gap and into operative engagement with the cam follower.

18. A builder mechanism for use in a machine of the class described, said builder mechanism comprising a traverse lever, a main traverse cam operative at times to oscillate the traverse lever through an arc of normal extent whereby to produce a normal traverse, a short traverse cam operative at the beginning of the building action to prevent effective operation of the main traverse cam, said short traverse cam being operative at times, while the main traverse cam is ineffective, to oscillate said lever through an arc of intermediate extent, thereby to produce a short traverse, a bunch building cam operative at the initiation of the building action to prevent effective operation of the short traverse cam, said bunch building cam being operative while the main traverse cam and the short traverse cam are ineffective to oscillate the lever through an arc of short extent, thereby to form a preliminary bunch adjacent to one end of the bobbin, and means operative automatically to determine the period of operation of the short traverse cam before the long traverse cam becomes effective.

19. A builder mechanism for use in a machine of the class described, said builder mechanism comprising a traverse lever, a main traverse cam operative at times to oscillate the traverse lever through an arc of normal extent whereby to produce a normal traverse, a short traverse cam operative at the beginning of the building action to prevent effective operation of the main traverse cam, said short traverse cam being operative at times, while the main traverse cam is ineffective, to oscillate said lever through an arc of intermediate extent, thereby to produce a short traverse, a bunch building cam operative at the initiation of the building action to prevent effective operation of the short traverse cam, said bunch building cam being operative while the main traverse cam and the short traverse cam are ineffective to oscillate the lever through an

arc of short extent, thereby to form a preliminary bunch adjacent to one end of the bobbin, and means operative to advance an element of the short traverse mechanism when the apparatus is made ready for doffing, thereby to restore said 5 element to starting position.

20. A builder mechanism for use in a machine of the class described, said builder mechanism comprising a traverse lever, a main traverse cam operative at times to oscillate the traverse lever through an arc of normal extent whereby to produce a normal traverse, a short traverse cam operative at the beginning of the building action to prevent effective operation of the main traverse cam, said short traverse cam being operative 15 at times, while the main traverse cam is ineffective, to oscillate said lever through an arc of intermediate extent, thereby to produce a short traverse, a bunch building cam operative at the initiation of the building action to prevent effective operation of the short traverse cam, said bunch building cam being operative while the main traverse cam and the short traverse cam are ineffective to oscillate the lever through an arc of short extent, thereby to form a preliminary 20 bunch adjacent to one end of the bobbin, and means operative automatically to reset the bunch building and short traverse mechanisms to starting position when the apparatus is made ready for doffing.

21. Apparatus for building a yarn mass including a preliminary bunch comprising superimposed short layers each of substantially uniform wind and length and secondary longer layers each also of substantially uniform wind and length overlapping the short layers, and a body winding comprising superimposed layers each longer than the secondary longer layers and each of substantially uniform wind and length, each successive layer of the bunch and of the secondary 35 layers being advanced beyond the preceding layer, said apparatus comprising a yarn traverse element, a traverse lever, a plurality of traverse cams each individually operative to impart a movement of fixed predetermined length respectively to the lever, and advance means operative to transmit movement from the traverse lever to the yarn traversing element, said advance means being constructed and arranged to impart a progressive increase in advance movement to the 40 traversing element while winding the bunch forming and the secondary layers and to maintain a uniform advance movement of the traversing element while winding the body layers.

JOHN S. FURTADO, JR. 55
